SHADE ROLLER

Elmer F. Pidgeon, Spiceland, Ind.

Application April 25, 1945, Serial No. 590,192

1 Claim. (Cl. 160—313)

1

The present invention appertains to new and useful improvements in shade rollers of the type containing a spring and shaft and wherein the shaft is journaled through a cup plate or like end member.

An important object of the present invention is to provide a readily removable cup plate which can be readily removed from the roller to permit access to the spring and shaft, to the end that repairs and replacements can be made more readily than is now possible with the conventional roller construction.

Another important object of the invention is to provide a shade roller of sheet metal construction, thus enhancing lightness in weight and perhaps economy of construction without sacrificing strength.

Still another important object of the invention is to provide a shade roller of sheet metal construction which promotes not only lightness in weight, resistance to wear, and other factors, but principally increases durability.

A further object of the invention is to provide a shade roller constructed of metal, plastic, or some other material capable of being formed with threads at one end to receive a threaded coupling, which can be readily removed when repairs and replacements of internal parts become necessary.

Still a further object of the invention is to provide a shade roller wherein either one or both end plates can be constructed to permit removability, without sacrificing the normal strength of the roller and definitely increasing accessibility to the internal elements of construction.

Various other important objects and advantages of the invention will become apparent to the reader of the following description.

In the drawings:

Figure 1 is a fragmentary side elevational view of the improved roller.

Figure 2 is a fragmentary longitudinal sectional view through the improved roller.

Figure 3 is an end elevational view of the roller showing a portion broken away.

Figure 4 is an enlarged fragmentary detailed sectional view taken on line 4—4 of Figure 1.

Referring to the drawings, wherein like numerals designate like parts, it can be seen that numeral 5 denotes the roller proper which consists of an elongated cylindrical shell preferably of a metallic alloy, but which can be of some plastic material, or other material suitable for the purpose, and which can be moulded or otherwise reformed to provide an elongated trough 6 for re-

ceiving the usual hem 7 and contained rod or anchoring element 8 of a window shade 9.

A shade roller includes a shaft 10 and a spring 11. One end of the roller generally has a round or cylindrical pindle, while the distal end of the roller and more specifically the corresponding end of the shaft 10 has a key or flattened extension 12. This end of the shaft 10 is normally journaled through a cup plate, but in the instance of 10 the present invention, numeral 13 denotes a cup plate, the peripheral portion of which is formed with threads coefficient to internal threads 14 formed within the adjacent end portion of the roller 5.

More or less conventionally the shaft 10 is provided at the outside of the cup plate 13 with a formation 15 formed with recesses or shoulders with which pawls 16 are cooperative, obviously to prevent the return movement of the shade 20 roller.

It is preferable that the roller 5 at opposite sides of the trough 6, at the cup plate end thereof (or at each end should both end plates be removable) be formed with openings to accommodate set screws 17 which can be driven into threaded openings in the peripheral portion of the roller 5. Thus it can be seen that with the set screws 25 located adjacent to and at opposite sides of the trough 6, the trough construction will be reinforced and definitely determined with respect to 30 expansiveness.

It can now be discerned that the principal purpose in having the cup plate or plates 13 removable is so that ready access can be obtained to the 35 interior of the roller in order that the internal parts can be removed for the purpose of repairs or replacements.

Obviously, by removing the set screw 17, the 40 end plate 13 is freed to the extent that it can be unscrewed from the roller 5, thus freeing the shaft 10 and spring 11 so that these parts can be replaced or repaired as the occasion demands.

While the foregoing description sets forth the 45 invention in specific terms, it is to be understood that numerous changes in the shape, size and materials may be resorted to without departing from the spirit and scope of the invention as claimed hereinafter.

50 Having described the invention, what is claimed as new is:

A shade roller comprising a roller shell, a shaft 55 extending into the shell, a bracket engaging key at one end of the shaft, spring means between the shaft and the shell, a closure member for the

shell at the keyed end of the shaft, said closure member being readily removable to permit access to the shaft and spring, said member being provided with peripheral threads, said shell being provided with internal threads to accommodate the first-mentioned threads.
